UNITED STATES PATENT OFFICE

FREDERICK WILFRID ALEXANDER, OF LONDON, ENGLAND

FORMATION OF SELVEDGES FOR FABRICS

Application filed December 20, 1929, Serial No. 415,540, and in Great Britain December 27, 1928.

The invention relates to appliances for forming selvedges for belting or other fabrics by power operated looms, for example in the application of selvedges to the edges of belting, the selvedge consisting of a material which is adapted to withstand the wear due to belt forks, flanged pulleys or other rubbing surfaces.

According to the invention, the selvedge comprises two or any even number of twisted cords laid side by side in the same vertical plane, that is, in a plane at right angles to that of the body of the fabric. Each cord comprises, preferably, two twisted threads and each thread may consist of any number of separate strands.

The apparatus comprises for each selvedge a drum to which a partial rotation is intermittently applied by a device, preferably of the Maltese cross type. Two parallel sets of holes are provided in the periphery of the drum into which removable pins are placed so that, on the rotation of the drum, pivoted drop levers are raised by engagement with the pins and, in their raised positions, are adapted to be set into reciprocating motion, which by suitable connections imparts a limited angular rotation to discs carrying the bobbins for the twisted threads of which each cord of the selvedge consists.

In a preferred form of the apparatus, each drop lever is provided with a head adapted to engage, when raised by the pins on the periphery of the drum, with a horizontally reciprocating block when the block is moving in one direction, but to be released from it on the return movement of the block. The horizontal movement of the drop levers is transmitted by suitable means, for example pitch chains gearing with free-wheels, to the discs carrying the bobbins for the threads.

The blocks may be reciprocated by connecting rods pivoted to crank discs rotated by shafts driven from the driving shafts of the loom.

The bobbin carriers of the cords of the same selvedge are twisted to the same pitch but in opposite directions of twist and all the bobbin carriers are rotated simultaneously.

By the arrangement of the pins on the drums and the timing of the intermittent rotation of the drums, the twisting of the cords can be effected to suit the other weaving requirements.

In the accompanying drawings which represent an example of an appliance to be attached to a loom for forming a selvedge at each edge of a belt or other fabric—

Fig. 1 is a diagrammatic elevation and Fig. 2 a plan of the appliance and Fig. 3 is a detail showing a belting in plan on a reduced scale.

Figs. 4, 5 and 6 show the fabric with the selvedge cords.

In the example illustrated each edge of the belting is protected by a pair of twisted cords, the cords being laid side by side vertically over one another. In Fig. 3, a' , a^2 are the two threads of the upper twisted cord of the right-hand selvedge, a^3 , a^4 are the similar threads of the upper cord of the left-hand selvedge. Similar sets of threads, lying below those shown in Fig. 3, as shown in Figs. 5 and 6, form the lower pair of cords. The threads a' , a^2 are wound on bobbins b' , b^2 carried by a disc B' secured to a spindle x' on which is loosely mounted a sprocket wheel C' having one way ratchet engagement with said spindle. The threads a^3 , a^4 are wound on bobbins carried in the same way by a disc B^2 secured to a spindle x^2 on which is mounted a ratchet sprocket wheel C^2 .

Ratchet sprocket wheels C^3 , C^4 are similarly mounted, respectively, on the spindles x^3 and x^4 of the bobbin carriers B^3 and B^4 for the bottom pair of selvedge cords. The spindles x' , x^2 , x^3 and x^4 are adapted to rotate in one direction only. Each thread a' , a^2 etc. may be formed of several strands.

The mechanism is arranged to impart an angular movement intermittently to the sprocket wheels C' , C^2 , C^3 and C^4 on the spindles x' , x^2 , x^3 and x^4 of the discs B' , B^2 and B^3 , B^4 carrying bobbins for the cords on the same selvedge; these angular rotations are in opposite directions, so that the twists imparted to these two cords are of opposite hands, enabling the cords of the same pair to lie closely in contact.

The bobbin carrier B^3 is similarly mounted on a spindle x^3 directly below the spindle x' .

The bobbin carriers B^2, B^4 for the selvedge at the other edge of the fabric are similarly mounted on shafts x^2, x^4 rotated by the sprocket wheels C^2, C^4 .

The loom itself may be of known construction, such, for example, as that shown and described in U. S. Patent No. 587,349, granted August 3, 1897 to Louis P. Warner, and the threads of the selvedge cords may be shed, during the weaving of the fabric, by means such as shown and described in that patent.

During one to-and-fro movement of the shuttle the thread next to the warp at one edge of the fabric will be lifted to permit the shuttle to pass beneath the same and bind it to the fabric and the thread next to the warp at the opposite edge of the fabric will be out

of the way of the shuttle to permit the shuttle to bind the warp threads at that edge of the fabric. During the next to-and-fro movement of the shuttle the first named thread will be lifted out of the way of the shuttle to permit the shuttle to bind the warp threads at

that edge of the fabric and the second named threads will be lifted to permit the shuttle to pass beneath the same and bind it to the fabric. The twist imparted to the threads to form the cords themselves is timed, in relation to the movement of the shuttle and the advance of the fabric as the latter is woven, by engagement of the pin h on the disc H with the Maltese cross disc I .

The required angular movements of the bobbins is obtained as follows:—

A shaft D is rotated continuously by a sprocket wheel d actuated by a sprocket chain d' connected to a sprocket wheel driven by the loom shafting. A sprocket wheel E on the shaft D rotates a shaft F by means of a sprocket wheel G and chain g ; a disc H on the shaft F carries a pin h which imparts an intermittent angular movement to a disc I of the Maltese cross type secured to a spindle i on which are keyed drums J, K each provided with two sets of holes j', j^2 or k', k^2 , respectively, in which removable pins l or the like are inserted. The holes are arranged around the periphery of the drums in two planes at right angles to the axis of the drum. The pins inserted in the drum J are adapted to engage, as the drum rotates, respectively, with the lower surfaces of two horizontal pivoted drop levers M^2, M^4 . The lever M^4 is pivoted at m^4 to a bar N^4 pivoted at n^4 .

The drop lever M^2 which is parallel to the drop lever M^4 is pivoted at m^2 to a bar N^2 pivoted at n^2 . The levers M^2, M^4 are intermittently raised by the pins l and, when raised, are caused to execute a horizontal reciprocating movement by the following device:

On the shaft D are secured two crank discs O', O^2 each provided with an eccentric pin

y' or y^2 to which are pivoted connecting rods P', P^2 . Pins p', p^2 on the other ends of the connecting rods are connected to blocks Q', Q^2 which, on the rotation of the shaft D , move to and fro in a horizontal direction in guides q', q^2 . The levers M^2, M^4 are provided with inclined notches m as shown in Fig. 1, which, when the bars have been raised by the pins l on the drum J , are engaged by the inclined heads of the block Q' and moved to the right, rocking the levers N^2, N^4 clockwise about their pivots n^2, n^4 . The lever N^4 imparts an anticlockwise angular movement to the sprocket C^4 and thereby to the bobbin carrier B^4 by a chain R^4 carried over a guide roller S' and tensioned by a spring T^4 . A clockwise angular movement is imparted to the sprocket wheel C^2 and to the bobbin carrier B^2 by the horizontal movement of the drop lever M^2 through the corresponding lever N^2 and chain R^2 . The drop levers M^2, M^4 are returned to their original positions by the springs T^2, T^4 as the connecting rod P' is moved to the left by the crank disc O' .

Similar devices are provided for rotating the sprocket wheels C', C^3 and to the bobbin carriers B', B^3 by the levers N', N^3 operated by the drop levers M', M^3 , the heads of which have notches inclined in the opposite direction to those of M^2, M^4 , so that they are actuated by the block Q^2 in its movement from right to left; as the pin y^2 of the crank disc O^2 is in a position 180° from that of the pin y' , the movement of all the sprocket wheels $C—C^4$ and of the bobbin carriers $B'—B^4$ is effected at the same time.

The chains R', R^2, R^3 and R^4 have one of their ends connected, respectively, to the levers N', N^2, N^3 , and N^4 and their opposite ends connected, respectively, to springs T', T^2, T^3 , and T^4 . The chain R^2 passes around the sprocket wheel C^2 in a direction to rotate such sprocket wheel and the shaft x^2 on which it is mounted in a clockwise direction when the lever N^2 is rocked to the right (Figure 1) and the chain R^4 passes over the sprocket wheel C^4 in a direction to rotate such sprocket wheel and the shaft x^4 on which it is mounted in a counter-clockwise direction when the lever N^4 is rocked to the right. Similarly, the chain R' passes over the sprocket wheel C' in a direction to rotate such sprocket wheel and the shaft x' by which it is carried in a counter-clockwise direction when the lever N' is rocked to the left, and the chain R^3 passes over the sprocket wheel C^3 in a direction to rotate such sprocket wheel and the shaft x^3 by which it is carried in a clockwise direction when the lever N^3 is rocked to the left. The chains R^4 and R^3 also pass, respectively, over pulleys S' and S^2 mounted, respectively, between their respective sprocket wheels C^4, C^3 and actuating levers N^4 and N^3 . Since the

sprocket wheels C' , C^2 , C^3 and C^4 have ratchet engagement with the shafts x' , x^2 , x^3 and x^4 on which they are respectively mounted, they are free, when the levers N' and N^3 are rocked to the right and the levers N^2 and N^4 are rocked to the left, to rotate in reverse directions without imparting movement to said shafts.

Each of the double twisted selvedge cords, such as a' , a^2 on one edge of the fabric and a^3 , a^4 on the other edge, is caught up by the weft threads u in the process of weaving, as shown in Fig. 4, which secures the selvedges to the fabric.

As shown in Fig. 4, the weft passes round the inside member such as a' of one pair of twisted cords at the left selvedge and then across the warp threads v to a point just inside the pair of twisted cords a^3 , a^4 at the right edge, returns to a point inside the cord a' , a^2 , again passes across the warp and around the inside member a^4 of the twisted cord a^3 , a^4 and so on.

Upper and lower pairs of twisted selvedge cords are shown in Figs. 5 and 6, but only the upper cords of each pair a' , a^2 and a^3 , a^4 bear reference characters.

I claim:—

1. In a loom provided with shedding means and weft inserting means, apparatus for forming a selvedge at each longitudinal edge of a fabric, said apparatus comprising a pair of rotatable shafts, a bobbin carrier on each of said shafts, and a pair of bobbins on each carrier for supplying the threads to be twisted together to form a cord, means for imparting rotation to said shafts, said means comprising a pair of pivoted levers, means connecting each of said levers to one of said shafts for intermittently and simultaneously rotating said shafts in opposite directions when said levers are rocked, and means for intermittently rocking said levers.

2. In a loom provided with shedding means and weft inserting means, apparatus for forming a selvedge at each longitudinal edge of a fabric, said apparatus comprising a pair of rotatable bobbin carrier shafts, a bobbin carrier on each of said shafts, and a pair of bobbins on each carrier for supplying the threads to be twisted together to form a cord, means for actuating said shafts, said means comprising a pair of pivoted levers, a sprocket wheel on each of said shafts, flexible means connected to said levers and passing over said sprocket wheels, and means for intermittently rocking said levers to simultaneously and intermittently impart angular movements of the same extent in opposite directions to said shafts.

3. In a loom provided with shedding means and weft inserting means, apparatus for forming a selvedge on opposite edges of a fabric, said apparatus comprising a pair of rotatable shafts, a bobbin carrier on each of

said shafts, and a pair of bobbins on each carrier for supplying the threads to be twisted together to form a cord, means for actuating said shafts, said means comprising a pair of pivoted levers, a sprocket wheel on each of said shafts, chains connected to said levers and passing over said sprocket wheels for imparting angular movements of the same extent simultaneously and intermittently in opposite directions to said shafts when said levers are rocked in one direction, means for intermittently rocking said levers in one direction, and elastic means for maintaining said chains under tension and rocking said levers in the opposite direction.

4. In a loom provided with shedding means and weft inserting means, apparatus for forming a selvedge at each longitudinal edge of a fabric, said apparatus comprising a pair of rotatable shafts, a bobbin carrier on each of said shafts, and a pair of bobbins on each carrier for supplying the threads to be twisted together to form a cord, means for actuating said shafts, said means comprising a pair of pivoted levers, a pair of sliding blocks, means for reciprocating said blocks, each block intermittently engaging with and rocking one of said levers, and means connecting said levers and said rotatable shafts for simultaneously and intermittently imparting angular movements in opposite directions to said shafts.

5. In a loom provided with shedding means and weft inserting means, apparatus for forming a selvedge at each longitudinal edge of a fabric, said apparatus comprising a pair of rotatable shafts, a bobbin carrier on each of said shafts, and a pair of bobbins on each carrier for supplying the threads to be twisted together to form a cord, means for actuating said shafts, said means comprising a pair of pivoted levers, a pair of sliding blocks, means for reciprocating said blocks, said blocks intermittently engaging with and rocking said levers in one direction, a sprocket wheel on each of said rotatable shafts, chains connected to said levers and passing over said sprocket wheels for imparting angular movements simultaneously and intermittently in opposite directions to said rotatable shafts and means elastically maintaining said chains under tension and returning said levers to normal position.

6. In a loom provided with shedding means and weft inserting means, apparatus for forming a selvedge at each longitudinal edge of a fabric, said apparatus comprising a pair of rotatable shafts, a bobbin carrier on each of said shafts, and a pair of bobbins on each carrier for supplying the threads to be twisted together to form a cord, means for actuating said shafts, said means comprising a pair of pivoted levers, a continuously rotating shaft, a pair of sliding blocks above said levers and actuated by said con-

tinuously rotating shaft, means for intermittently lifting said pivoted levers into engagement with said sliding blocks to rock said levers, and means connecting said levers and said rotatable shafts for simultaneously and intermittently imparting angular movements in opposite directions to said shafts.

7. In a loom provided with shedding means and weft inserting means, apparatus for forming a selvedge at each longitudinal edge of a fabric, said apparatus comprising a pair of rotatable bobbin carriers, and a pair of bobbins on each carrier for supplying the threads to be twisted together to form a cord, means for actuating said bobbin carriers, said means comprising a pair of pivoted levers, a continuously rotating shaft, a connecting rod actuated by said shaft, a pair of sliding blocks adjacent said levers and reciprocated by said rod, means for intermittently shifting said pivoted levers into engagement with said sliding blocks, a sprocket wheel associated with each of said rotatable bobbin carriers, chains connected to said levers and passing over said sprocket wheels for imparting angular movements simultaneously and intermittently in opposite directions to said bobbin carriers when said levers are rocked in one direction, and yielding means maintaining said chains under tension and urging said levers toward their normal positions.

8. In a loom provided with shedding means and weft inserting means, apparatus for forming a selvedge at each longitudinal edge of a fabric, said apparatus comprising a pair of rotatable shafts, and a bobbin carrier on each of said shafts, a pair of bobbins on each carrier for supplying the threads to be twisted together to form a cord, means for actuating said rotatable shafts, said means comprising a pair of pivoted levers, a pair of sliding blocks, means for reciprocating said blocks, said blocks being engageable respectively with said levers for rocking said levers in opposite directions, a rotatable drum, actuated by said block-reciprocating means, a pair of rows of pins spaced equidistantly around the periphery of said drum, the pins of each row adapted to successively engage and raise one arm of one of said pivoted levers into engagement with its associated sliding block to rock said lever, and means connecting each of said levers to one of said rotatable shafts for simultaneously and intermittently imparting angular movements in opposite directions to said shafts.

9. In a loom provided with shedding means and weft inserting means, apparatus for forming a selvedge at each longitudinal edge of a fabric, said apparatus comprising a pair of rotatable shafts, a bobbin carrier on each of said shafts, and a pair of bobbins on each carrier for supplying the threads to be

twisted together to form a cord, a pair of pivoted levers each having a notch in one of its arms, a block having means for engagement with the notches of said levers, means for reciprocating said block, a drum rotated by said block reciprocating means and having pins spaced around its periphery to bear against said levers and bring the notches of the latter into the path of movement of the notch engaging means of said sliding block, and means connecting said levers and said rotatable shafts for simultaneously and intermittently imparting angular movements in opposite directions to said rotatable shafts.

10. In a loom provided with shedding means and weft inserting means, apparatus for forming a selvedge at each longitudinal edge of the fabric, said apparatus comprising a pair of rotatable shafts, a bobbin carrier on each of said shafts, and a pair of bobbins on each carrier for supplying the threads to be twisted together to form a cord, means for actuating said shafts, said means comprising a pair of pivoted levers, a sliding block, means for reciprocating said block, a rotatable shaft, a Maltese cross on said rotatable shaft, a drum rotated intermittently by said cross, pins spaced around the periphery of said drum to engage and simultaneously rock said pivoted levers, each of said levers having a notch in one of its arms and said sliding block having a beveled end to engage the notches of said levers to rock said levers, a second rotatable shaft actuated by said block-reciprocating means and having a pin to successively engage and rotate said Maltese cross, and means connecting said levers and said bobbin carrier shafts for imparting angular movements simultaneously and intermittently in opposite directions to said bobbin-carrier shafts.

In testimony whereof I have signed my name to this specification.

FREDERICK WILFRID ALEXANDER.
